UNITED STATES PATENT OFFICE

173,072

PORTABLE INTERNAL-COMBUSTION ENGINE

Leo J. Lechtenberg and Clifford Brooks Stevens,
Milwaukee, Wis., assignors to Briggs & Stratton
Corporation, Milwaukee, Wis., a corporation of
Wisconsin

Application January 4, 1954, Serial No. 28,337

Term of patent 14 years

(Cl. D77—1)

To all whom it may concern:

Be it known that we, Leo J. Lechtenberg and Clifford Brooks Stevens, both citizens of the United States, residing at Milwaukee, in the county of Milwaukee and State of Wisconsin, have invented a new, original, and ornamental Design for a Portable Internal Combustion Engine, of which the following is a specification, reference being had to the accompanying drawings, forming part thereof.

Figure 1 is a perspective view looking down on a portable internal combustion engine embodying our new design, and showing the top and two adjacent sides thereof;

Figure 2 is a perspective view similar to Figure 1 but showing the top and the remaining two adjacent sides of the engine;

Figure 3 is a plan view thereof;

Figure 4 is an elevational view showing one side of the engine; and

Figure 5 is an elevational view showing the opposite side of the engine.

The dominant features of our design reside in those portions thereof illustrated in full lines.

We claim:

The ornamental design for a portable internal-combustion engine, as shown and described.
